INNER SOLE FOR WELT SHOES

William L. Knipl, Haverhill, Mass., assignor to
 Knipl Bros., Inc., Ward Hill, Mass., a corpora-
 tion of Massachusetts

Application February 6, 1940, Serial No. 317,468

1 Claim. (Cl. 36—22)

This invention relates to certain improvements in welt shoes or in inner soles therefor of the type shown in the patent to Knipl #1,444,420, dated June 29, 1915.

While inner soles of the type disclosed in said patent have been successfully employed for many years in the construction of welt shoes, as their use enables the production of a shoe of this type which has a flexible fore part, an objection to the use of an innersole of this type has been that, if a metal shank stiffener is employed which extended for the full length of the shank portion, so as to provide an effective arch support, it was likely to become uncomfortable to the wearer, as its front end was likely to press inward sufficiently to cause a raised portion, or hump at the front end of the shank portion of the shoe.

For this reason the practice has been to employ a metal stiffener which extended forwardly only a short distance beyond the heel breast.

An objection to this arrangement was that the support which was provided for the longitudinal arch of the foot of the wearer was insufficient.

The object of my invention is to provide an inner sole of the type above referred to which will have a sufficiently flexible forepart and which, at the same time will enable a full length metal shank stiffener, or arch support to be employed in the construction of the shoe without causing discomfort to the wearer and without decreasing the flexibility of the portions of the shoe which it is desirable to be made flexible.

I accomplish this object by providing the inner sole with a reinforcing portion which extends over the entire portion of the shank in which the metal shank support is to be located, and terminates approximately at the ball line, so that the forepart portion of the shoe will be as flexible as when provided with an innersole constructed as disclosed in said prior patent, and, at the same time, an effective arch support will be provided, which will not cause discomfort to the wearer by pressing inward against the flexible insole at its front end.

For a more complete disclosure of the construction which I employ reference is now made to the following specification, in connection with the accompanying drawing, in which:

Fig. 1 is a bottom plan view of an inner sole which I employ.

Fig. 2 is a longitudinal sectional view thereof, at line 2—2 of Fig. 1.

Fig. 3 is a plan view of the reinforcing section.

Fig. 4 is a longitudinal sectional view of the completed shoe.

As shown in the drawing, a shoe is provided with an inner sole which is constructed similarly to the inner sole disclosed in the said prior patent, as it comprises a sole section *a* of thin, soft leather, which has been split from the flesh side of a skin and cut out in complete sole shape, and a textile section *b* which consists of two layers of adhesively connected canvas, which is also cut out in complete sole shape but is slightly wider or larger than the section *a*, so that when laid flat thereon the edge portion thereof projects to a slight extent beyond the edges of the section *a* and is adapted to be turned up to provide a lip to which the welt and upper is attached.

According to my invention I provide the inner sole with a reinforcing section *c* of sheet material such as fiber, or leather, preferably the latter, and which extends from the heel end to the ball line, and has its front end portion skived to a thin edge, the section *c* being interposed between the sections *a* and *b* and the three sections being secured together by stitches *d*.

Before the outer sole is attached to the welt, a metal shank stiffener *g* is secured to the bottom side of the inner sole in such a position that it extends from some point in the heel portion, approximately an inch in the rear of the heel breast, close to the front end of the unskived portion of the section *c*, so that the full thickness of the section *c* will be interposed between the metal stiffener *g* and the top section *a*.

As thus arranged the reinforcing section *c* will prevent the front end portion of the metal stiffener from forcing up the inner sole portion directly thereabove, causing a hump which would be uncomfortable to the wearer, and at the same time the flexibility of the shoe is not impaired at any point where flexibility is desirable and the full benefit of a stiff, arch supporting shank is secured.

I claim:

An inner sole for welt shoes composed of a sole shaped top section of limp thin flexible sheet material having plane surfaces and being too thin for satisfactory channeling, and a sole-shaped bottom section of textile material having a down-turned edge portion providing a lip for attachment to an upper and a welt and disposed on and coextensive with one of the plane surfaces of the top section, a reinforcing section of relatively stiff sheet material disposed between said sections and coextensive in width therewith and extending from the heel end approximately to

the ball line and having its front end skived to a sharp edge, a line of stitching spaced from the edge of the sole shaped top section and extending through said textile material close to the down-turned edge portion thereof for securing the top section, the textile bottom section and the intermediate stiff sheet material together from about the heel breast line on one side of the sole around the forepart to about the heel breast line on the

other side of the sole, and a metal shank stiffener secured beneath and against the lower face of said textile section and extending from beneath the heel portion thereof and terminating at its front end closely adjacent but rearwardly of the ball line and beneath the reinforcing section, and in the rear of the skived portion thereof.

WM. L. KNIPE.
